(57) **CLAIM**

The ornamental design for an implant placement guide, as shown and described.

DESCRIPTION

FIG. 1 is a perspective view of our design for an implant placement guide.

FIG. 2 is a first side view of the design for the implant placement guide of FIG. 1;

FIG. 3 is a second side view of the design for the implant placement guide of FIG. 1;

FIG. 4 is a front view of the design for the implant placement guide of FIG. 1;

FIG. 5 is a back view of the design for the implant placement guide of FIG. 1;

FIG. 6 is a top view for the design for the implant placement guide of FIG. 1; and,

FIG. 7 is a bottom view for the design of the implant placement guide of FIG. 1.

The broken lines shown are included for the purpose of illustrating portions of the implant placement guide that form no part of the claim.
